UNITED STATES PATENT OFFICE

ANNA F. GIFFORD, OF ERIE, PENNSYLVANIA, ASSIGNOR TO ERIE DAY SCHOOL, OF ERIE, PENNSYLVANIA, A CORPORATION OF PENNSYLVANIA

DESIGN FOR A BOOKCASE

Application filed June 18, 1930. Serial No. 36,093. Term of patent 3½ years.

To all whom it may concern:

Be it known that I, ANNA F. GIFFORD, a citizen of the United States, residing at Erie, in the county of Erie and State of Pennsylvania, have invented a new, original, and ornamental Design for a Bookcase, of which the following is a specification, reference being had to the accompanying drawing, forming a part thereof, wherein—

Fig. 1 shows a perspective view of the front of the bookcase showing my new design.

Fig. 2, a perspective view of the rear of the bookcase.

I claim:—

The ornamental design for a bookcase as shown.

ANNA F. GIFFORD.
